ABSTRACT: A snap switch capable of unfailingly breaking open moving contacts disposed opposite fixed contacts.

It includes, in a housing carrying the fixed contacts, a rocking central part carrying the moving contacts and means for restraining it on the housing, a slide which is provided with at least one cam for directly actuating the central part and which extends therethrough, said part being provided with an elastic thrust point and a snap-action contact breaking spring being positioned between the slide and the central part whereby to cause operation of the slide cam on the central part whereby to cause operation of the slide cam on the central part to simultaneously arm the spring and raise the central part against the countering action of the elastic thrust point followed by sudden release of the central part and tripping thereof responsively to the spring, backup driving means being additionally provided to operate in the event of failure of the spring.

-FIG.13-

SNAP SWITCH WITH POSITIVE-DRIVE BREAKING ACTION

This invention relates to the snap switches used in industry to control the operation of machines and other mechanical devices and provides means for ensuring unfailing breaking of the contacts even if the springs for producing the snap effect or the elastic restoring action on the various moving parts were unable to function. Already known are many mechanically operated switches in which contacts are moved with a snap action even though the mechanical action itself may be very slow.

Also known is an electric switch which does not use the tumbler effect but comprises a slide and a switching element moving therealong. This switching element, which is restrained in either of the two switching positions by a locking member, changes its position responsively to a spring interposed between the slide and the switching element when the slide, which comprises a cam, unlatches the locking member and thereby releases the switching element. Said spring is contained in a guiding enclosure formed by the slide and the switching element.

In one prior art switch, a contact-bearer is connected to a beam-lever type mechanical member which is alternately restrained in two stable positions by hooked levers, with the actuating member first tensioning a spring and then releasing one of the levers. Should the spring break, however, the contact-bearer is no longer actuated. Furthermore, in cases where the switch is required to break fairly high current intensities, notably in direct current, the rupturing arc may in some cause the contacts to fuse together.

The above-mentioned switches do not normally include fail-safe drive means whereby the contacts are separated by a mechanical force in all cases. Moreover, prior art switches have often tended to be complicated and to include a large number of parts, hooking levers and springs.

The present invention overcomes these drawbacks and provides notable improvements. It relates to a basic switch of very simple design, in which the translating motion of an actuating slide causes moving contacts to be shifted with a snap action or through a direct drive should the snap action have been prevented. The invention further provides for a rotary wiping effect between the fixed and moving contacts.

The invention further relates to a lever-operated switch, usually known as a "limit switch," for use on machines for controlling the stroke or travel of the moving parts, said lever-operated switch being obtained by mechanically adapting the basic switch of this invention. Lastly, the invention relates to a method of elastically operating the switch lever that includes the use of a damping device for preventing the lever from hunting about its resting position.

Essentially, the snap switch of this invention is characterized in that it includes a central part having two stable positions and bearing moving contacts positioned opposite fixed contacts, means for securing the same to a fixed part of the switch and an elastic bearing point therefor, a slide comprising at least one actuating cam and extending through said central part, and a spring disposed within said central part and armed by said slide which, at the same time, lifts the central part until latching means are ultimately released and thereby allow the spring to relax and the central part to snap suddenly from one of its stable positions to the other, backup means being provided in the event of failure of the armed spring.

The description which follows with reference to the accompanying non-limitative exemplary drawings will give a clear understanding of how the invention can be carried into practice. In the drawings:

FIGS. 1 through 4 are side elevation views of the different operating configurations of one embodiment of a snap switch according to the invention.

FIG. 1a is a fragmental section taken through the line a-a in FIG. 1.

FIG. 1b is an alternative embodiment of the trip system and the method of fastening the spring of the central part in FIG. 1.

FIGS. 5 through 7 are partial longitudinal sectional views of still another embodiment of a snap switch according to the invention.

FIG. 8 is a cross-sectional showing of the embodiment of FIGS. 5 to 7.

FIG. 9 is a top view of the central part used in the embodiment of FIGS. 5 to 7.

FIG. 10 is a front view of a motion amplifier.

FIG. 11 is a top view in partial section of yet another embodiment of a snap switch according to this invention.

FIG. 12 is a fragmental longitudinal portrayal in section of the embodiment of FIG. 11.

FIG. 13 is a longitudinal sectional portrayal of a device for converting a rotating motion into a translational motion, applicable for controlling the slides of snap switches according to this invention.

FIG. 14 is a front view of a cam used in said motion converting device.

FIGS. 15 and 16 are front views of two dogs used in said motion converting device; and

FIG. 17 shows the said two dogs in their engaged configuration.

In the embodiment shown in FIGS. 1 to 4, the said switch according to the present invention includes a bridgeshaped central part 1 having four legs 2.

A slide 3 is movable along a slideway 4 formed in the switch housing 5 and is formed with two flanges 6, and each flange can pass between two of the legs 2 of central part 1.

The central part 1 is surmounted by a ring 7 through which extend two blades 8 bearing moving contacts (not shown for greater clarity), a spring 9 being interposed between the blades in said ring.

Fixed contacts (likewise not shown) are positioned opposite the moving contacts, which are four in number, each blade 8 carrying a moving contact on either side of the ring.

Each leg 2 is formed with two sloping facets: an outer facet 10 and an end facet 12. The outer facet 10 cooperates with a fixed lateral stop 13, and the end facet 12 cooperates turn with a fixed catch 14 and with a fixed ramp 15 extending up to the lateral stop 13.

The fixed stops 13, the fixed catches 14 and the fixed ramps 15 are formed on two members 16 rigid with the bottom of the main housing and positioned on either side of slide 3. Each member 16 comprises two stops 13, two catches 14 and two ramps 15.

The end facets 12 of legs 2 also cooperate with two cams 17 rigid with the slide.

Opposite the members 16, central part 1 is offered a resilient bearing point consisting of a ball or roller 18 upon which thrust is exerted by a spring 19 or by a spring blade.

A further spring 20 is placed longitudinally beneath bridgeshaped central part 1 in such manner as to be restrained, in the resting position shown in FIGS. 1 and 3, between the two flanges 6 of slide 3, and, in the operative position shown in FIGS. 2 and 4, between one of these flanges and a pair of legs 2 against which it abuts.

It will be clear from the foregoing that when the slide 3 is urged in the direction of arrow f in FIGS. 1 and 2, the flange 6 located on the side where pressure is exerted will pass between the legs 2 on that side and compress the spring 20 against the other two legs 2 of central part 1.

At the same time, the cams 17 act upon those end facets of the feet 2 which are opposite those traversed by the slide 50 flange 6 and raise central part 1 until the facets 12 of said feet have ridden over the peaks of cams 17 and until said feet disengage from catches 14. At this point the spring 20 relaxes and suddenly thrusts back the central part until it occupies the resting position shown in FIG. 3, which is symmetrical with that shown in FIG. 1.

In the case of action exerted in the direction of arrow f_2 in FIG. 3, central part 1 is caused to snap over into the symmetrical position of FIG. 1 when, here again, the feet 2 opposite those traversed by the slide flange in question ride over the peaks of cams 17 and disengage from catches 14.

In the case of action exerted in the direction of either arrow f_1 or arrow f_2 , the facets 12 on the feet opposite those traversed by the flange 6 in question slide along the ramps 15 as the central part 1 snaps over, with the facets 10 of said feet abutting against the stops 13 located before them.

Each time the central part 1 snaps over, the moving contacts are caused to snap open.

The preliminary lifting motion of central part 1 produces a wiping effect between the fixed and moving contacts.

Should central part 1 be unable to snap over, a peg 21 (FIG. 4) positioned on the peak of each cam 17 acts upon those feet 2 which are opposite the ones traversed by one of the flanges 6 of slide 3, if force continues to be exerted on the slide.

In the embodiment shown in FIGS. 5 through 10 the snap switch according to this invention includes a central indented part 1a provided with two lateral rings 7a (FIGS. 7 and 8), each of which is traversed by two blades 8a bearing moving contacts 22 on either side of the ring. A spring 9a is interposed between the two blades.

Fixed contacts 23 equal in number to the moving contacts 22 are disposed on strips 24 rigid with the main housing.

Two pairs of catches 25 are formed respectively on two of the faces of central part 1a and are adapted to engage in corresponding indents 26 formed in fixed parts 27 on the main housing (see FIGS. 7 and 9).

The central part is traversed by a slide 3a formed with a camming indent 17a which cooperates with an internal lobe 28 on central part 1a.

A spring 20a is lodged inside the central part in such manner as to be restrained, in the resting position, between two facing protrusions 29 on slide 3a and, in operation, between one of these protrusions and an abutment wall 30 (FIG. 8) provided on either side of the slide, within the indentation of the central part.

A roller 18a supported on a spring lodged inside the central part is interposed between the latter and the slide.

A push (f_1 , FIG. 5) or a pull (f_2 , FIG. 6) exerted on slide 3a causes central part 1 to be raised and simultaneously arms the spring 20a by compressing it between one of the protrusions 29 on the slide and one of the abutment walls 30 on the central part.

The raising effect is obtained by the cooperation of hollow camming surface 17a with lobe 28 on the central part.

In the course of the raising process the catches 25 disengage from their indents 26 and the armed spring 20a relaxes, causing the central part to snap over from one tilted position to another tilted position symmetrical therewith (from FIG. 5 to FIG. 6, or vice versa).

Should snapover of the central part be unable to take place, a plate 31 on the slide acts upon the central part so as to cause it to trip. A forked amplifier device 32 (FIG. 10) may be interposed to that end between plate 31 and the central part. Obviously, two plates 31 and two amplifier devices 32 are provided to operate respectively for operation in the direction f_1 and in the direction f_2 .

In the embodiment shown in FIGS. 11 and 12, control is positive only in the direction f_1 and is automatic in the opposite direction by virtue of a return spring 33. The latter is interposed between the main housing and a protrusion 34 on the slide 3b, which comprises only one actuating plate 31b; only one amplifier device 32 is accordingly provided.

The slides may be actuated either off a part possessed of translational reciprocating motion or off a part possessed of rotating motion about a midway position (as in the case of a machine-tool component, for instance).

In the latter case, it is necessary to provide means for converting a rotary motion into a linear motion.

FIG. 13 illustrates a device which permits such conversion and additionally enables a controlled lever 35 to return into its midway position. Means are also provided to limit the angular travel of the controlled lever about its midway position.

Lever 35 is angularly rigid with an axle 36 forming an extension of a shaft 37 carrying a cam 38 formed with a lobe 38a and an indent 38b.

From either side of lobe 38a extend circle-arcuate ramps 39 which terminate on a diameter of the cam at right angles to the diameter joining the lobe to the indent. From either side of indent 38b extend circle-arcuate ramps 40 terminating on the same diameter. The radius of ramps 39 is smaller than that of ramps 40.

Lobe 38a, indent 38b and ramps 39 and 40 cooperate with cam followers 41 carried on a slide 42 which is movable within a slideway 43 and guided by a stud 44.

Slide 42 bears an arm 45 capable of being adapted upon the slide 3 of a snap switch according to the invention, the housing of which is designated by reference numeral 5.

Motion of the cam 38 accordingly causes translational motion of slide 42 and hence of the switch slide 3.

Arm 45 may be caused to operate either on a slide designed for two positive displacements (3 and 3a) or on one designed for only one positive displacement (3b).

Carried on shaft 37 are two dogs 46 and 47. Dog 46 (FIG. 15) is free to rotate over ninety degrees in the direction f_3 and carries a tang 48 capable of rotating through 90 degrees between two fixed stops 49 and 50. Two lands 64 and 65 are formed inside this dog, on either side of shaft 37. The sides 70, 71 of these lands act as abutments for the two ends respectively of a pin 66 extending through shaft 37.

The dog 47 (FIG. 16) is free to rotate over 90 degrees in the direction f_4 and carries a tang 51 capable of rotating through 90 degrees between two fixed stops 52 and 53. Two lands 67 and 68 are likewise formed within dog 47, on either side of shaft 37, but are angularly offset by 90 degrees in relation to lands 64 and 65. A pin 69 extends through shaft 37 so that its two ends may bear against the sides 72, 73 of lands 67 and 68.

When lever 35 is actuated in the direction f_3 , shaft 37 moves pin 66 into abutment against the sides 70 and 71 of lands 64 and 65, respectively, of dog 46, thereby rotating the latter whereas dog 47 does not rotate but shifts along shaft 37 and compresses a spring 57 interposed between dog 47 and a fixed wall 58. The rotation of dog 46 is limited by the stops 49 and 50.

When lever 35 is actuated in the direction f_4 , pin 69 is in abutment against the sides 72 and 73 of lands 67 and 68 respectively of dog 47, thereby rotating the latter whereas dog 46 does not rotate.

As it rotates, dog 47 is displaced longitudinally in the direction f_5 along shaft 37 and compresses spring 57.

When spring 57 relaxes, lever 36 is restored to its midway or resting position.

Spring 57 is engaged over a cylinder 60 which is rigid with dog 47 and embodies two blind holes 61 and 62. Blind hole 61 is adapted to receive the end of shaft 37. In conjunction with a cylindrical head 63 rigid with fixed wall 58, blind hole 62 forms a dashpot which prevents lever 35 from oscillating about its resting position.

We claim:

1. A snap switch which operates from one stable position to another stable position and is capable of unfailing opening of contacts, comprising:

a housing having fixed contacts attached to said housing;

a rocking central part having moving contacts attached thereto and mounted in said housing to move from one stable position to another;

latching means on said central part and means engageable with said latching means for holding said central part against movement;

a slide provided with at least one cam means engageable with said central part for releasing said latching means from said means engageable with said latching means and

said slide mounted for reciprocating motion in said housing;
 said central part having an opening therethrough and said slide positioned for at least a portion of said slide to pass through said opening;
 a resilient thrust point means in operative contact with said central part to restrain the movement of said central part from one of its stable positions to another;
 a spring mounted for compression between a surface on said slide and an opposing surface on said central part at least during reciprocal movement of said slide; and
 supplemental switch drive means on said slide for engaging said central part during a portion of the reciprocating motion of said slide when said rocking central part has failed to move to its other stable position during the reciprocating motion of said slide, to move said central part off of a stable position.

2. A switch in accordance with claim 1 further characterized by said means engageable with said latching means mounted rigidly to said housing.

3. A switch in accordance with claim 1 further characterized by said central part having the shape of a bridge with two pairs of legs; and
 said slide having a flange on each side, each of said flanges located to pass between one of said pairs of legs on said central part and compress said spring between said flange and the other of said pair of legs.

4. A switch in accordance with claim 3 further characterized by said latching means formed by the end portions of said legs;
 said means engageable with said latching means mounted rigidly to said housing;
 and said resilient thrust point formed on said housing.

5. A switch in accordance with claim 3 further characterized by said supplemental switch drive means being protrusions on said cam means whereby operation of the switch will take place despite any failure of said spring.

6. A switch in accordance with claim 1 further characterized by the opening in said central part being an indentation which accommodates said slide therein;
 said slide having an indentation which accommodates said spring; and
 said resilient thrust point being located between said slide and said central part.

7. A switch in accordance with claim 6 further characterized by said supplemental switch drive including:
 10 plates forming part of said slide on the end portions of said slide; and
 an intermediate member between each of said plates and said central part.

8. A switch in accordance with claim 6 further characterized by said slide operating the switch during each direction of reciprocation of said slide; and
 15 said central part having the components of the switch symmetrically distributed on either side of said central part.

9. A switch in accordance with claim 6 further characterized by said slide operating the switch during only one direction of reciprocation of said slide;
 20 said supplemental switch drive including:
 a plate forming part of said slide on one end portion of said slide, and
 25 an intermediate member between said plate and said central part;
 and a return spring compressible between said housing and said slide on the opposite end of said slide from said plate.

10. A switch in accordance with claim 1 further characterized by means for converting rotary motion into translational motion including:
 30 an arm connected to said slide;
 a shaft;
 a pivotal control member in angularly rigid connection with said shaft;
 a cam in angularly rigid connection with said shaft and positioned for coacting with said arm.
